UNITED STATES PATENT OFFICE.

WILLIAM E. RYAN, OF WASHINGTON, DISTRICT OF COLUMBIA.

DESIGN FOR A BADGE.

SPECIFICATION forming part of Design No. 34,772, dated July 16, 1901.

Application filed June 18, 1901. Serial No. 65,068. Term of patent 3½ years.

To all whom it may concern:

Be it known that I, WILLIAM E. RYAN, a citizen of the United States, residing at Washington, District of Columbia, have invented and produced a new and original Design for Badges, of which the following is a full, clear, and exact description.

In the accompanying drawings, illustrating my design, Figure 1 is a front view, and Fig. 2 a central longitudinal section.

The leading or material features of my design, as shown in the drawings, consist of hemisphere A, representing North and South America, executed convex and having as dominant features the images of the Goddess of

Liberty and a female Spanish-American figure. On a flat disk B, depending from the hemisphere, is the image of a buffalo's head standing out in relief.

Having described my invention, what I claim as new, and desire to secure by Letters Patent, is—

The design for a badge, substantially as shown and described.

In testimony whereof I have hereunto set my hand the 17th day of June, A. D. 1901.

WILLIAM E. RYAN.

Witnesses:

ALEX. SCOTT,
ALBIN M. LONG.
